UNITED STATES PATENT OFFICE

2,538,120

AUDIBLE AERIAL TOP

Thomas I. Nakano, Papaikou,
Territory of Hawaii

Application December 5, 1947, Serial No. 789,791

6 Claims. (Cl. 46—61)

1

This invention relates to a novel audible toy and constitutes an improvement on my prior U. S. Letters Patent No. 2,219,236, issued October 22, 1940 and entitled Musical Toy.

It is a primary object of the present invention to provide a toy having a revolvable body to the ends of which are anchored the ends of a string or flexible member for suspending said body substantially horizontally therebetween whereby the body can be caused to revolve and wind the string ends onto the end portions of the body when the string is reciprocated vertically.

More particularly, it is an aim of the invention to provide a body formed of a molded resilient material having a chamber therein extending to adjacent the ends thereof and which conforms substantially to the external shape of the revolvable body.

Still another object of the invention is to provide a revolvable body which is elongated and tapered toward each end thereof and provided with means whereby the string ends or leads will grip the body when being wound thereon so that the convolutions of the string ends will extend toward the intermediate or central portion of the body.

Still a further object of the invention is to provide a hollow resilient body having a whistle mounted in a portion of the wall thereof and communicating with the atmosphere and with the body chamber whereby the toy will be rendered audible by the restriction and expansion of the body chamber.

Still another object of the invention is to provide an audible toy having means forming a part of the end portions of the body thereof to cause the string ends to wind thereon toward the central portion of the body for restricting the body chamber.

Various other objects and advantages of the invention will hereinafter become more fully apparent from the following description of the drawing, illustrating a preferred embodiment thereof, and wherein:

Figure 1 is a side elevational view of the toy;

Figure 2 is a longitudinal sectional view thereof taken substantially along a plane as indicated by the line 2—2 of Figure 1, and

Figure 3 is a cross sectional view through the central portion of the body of the toy.

Referring more specifically to the drawing, a novel audible toy in its entirety and which comprises the invention is designated generally 5 and includes an elongated body, designated generally 6 of substantially circular cross sectional shape and which tapers from the central portion there-

2

of toward each end to provide the corresponding tapered end portions 7 each of which terminates in a substantially spherical enlargement or knob 8 which is larger than the adjacent, outer end of the tapered portion 7 of which said knob or enlargement forms a part.

The body 6 is formed of a molded, resilient material, such as rubber, and is provided with a chamber 9 which extends longitudinally thereof and which is provided with corresponding tapered end portions extending into the tapered ends 7. The molded body 6 is internally thickened as seen in Figure 2 on either side of the intermediate portion of the chamber 9 to provide corresponding internal annular ribs or enlargements 10. Between the ribs or enlargements 10 a portion of the wall of the body 6 is provided with an opening 11 in which is anchored a whistle 12 of the type which will be sounded when air is forced therethrough, preferably in either direction.

The central portion of the exterior of the body 6 preferably has a picture 13 molded therein. The exterior of the tapered ends are preferably provided with grooves 14 extending therearound and arranged in cross relationship for providing a roughened surface at each end of the body 6, for a purpose which will hereinafter become apparent. The tapered end portions 7 may also be provided with projections 18 to additionally roughen the ends of the body 6, or said projections may be utilized alone in lieu of the grooves 14.

The end portions or leads 15 of a flexible member such as a cord or string, designated generally 16, are suitably tied or anchored at their terminals to the outer ends of the tapered body portions 7 inwardly of but adjacent the knobs 8, as seen at 17, in a manner so that the body 6 cannot rotate relatively to said anchored portions 17.

The cord or string 16 is grasped at an intermediate point for supporting the body 6 in substantially a horizontal position, as illustrated in Figure 1 after which the body 6 can be rotated on its longitudinal axis for winding the string ends or leads 15 onto the tapered body ends 7. The body 6 can then be released and by reciprocating the string or cord 16 vertically said body will be wound onto and off of the string ends 15, first in one direction and then in the other. The grooves 14 will afford a good gripping surface for the string ends 15 and so that they will not slide relatively to the tapered body ends 7 and will be wound inwardly thereon and toward the central portion of the body 6. A rapid deceleration of the translational movement of the body 6 just prior to completion of its downward movement and be-

fore beginning its upward movement will cause said body to be compressed for restricting the chamber 9 thereby exhausting the air under pressure through the opening afforded by the whistle 12 to thereby actuate the whistle and render the toy audible. Likewise, as the body 6 begins its upward movement the resiliency thereof will cause it to expand for drawing air into the chamber 9 to again actuate the whistle 12 and as the body approaches the upper extremity of its movement the cord ends 15 by being wound on the portion of the body in which the chamber 9 is formed will tend to compress said portion and restrict chamber 9 for again expelling air therefrom and actuating the whistle 12. The internally thickened ribs 10 will balance the body 6 for better maintaining it in a horizontal position while it is revolving and reciprocating upwardly and downwardly.

Various modifications and changes are contemplated and may obviously be resorted to, without departing from the spirit or scope of the invention as hereinafter defined by the appended claims.

I claim as my invention:

1. An audible toy of the character described comprising an elongated hollow body formed of a molded, resilient material and having tapered ends, a cord secured at its ends to the ends of said body; said body being provided with a chamber extending longitudinally thereof and having tapered end portions extending into the tapered ends of said body, and a whistle mounted in said body intermediate of its ends and communicating with said chamber and with the atmosphere, said body being revolved for winding the ends of the cord on the tapered ends of the body and for unwinding the cord ends therefrom whereby the deceleration and acceleration of the translational movement of said body will cause it to be compressed and expanded, respectively, for restricting and expanding the chamber for forcing the air outwardly and inwardly, respectively through the whistle.

2. A toy as in claim 1, said cord being adapted to be engaged intermediate of its ends for supporting the body in substantially a horizontal position and for causing the cord ends to be wound onto and off of the tapered ends of the body as the cord is reciprocated vertically, and the rapid deceleration of the translational movement of said body as it approaches the lower extremity of its movement functioning to compress the body and restrict the chamber thereof.

3. A toy as in claim 1, the end portions of said body being roughened for affording a good gripping surface for the cord ends to cause the cord ends to wind spirally thereon toward the central portion of the body for compressing said central portion and restricting the chamber thereof.

4. A toy of the character described comprising an elongated body formed of a molded, compressible material of circular cross section and having corresponding tapered ends, a string having its ends anchored to the tapered ends of said body and adapted to be manually supported intermediate of its ends for supporting the body in substantially a horizontal position whereby the cord ends will be wound onto and unwound from the tapered ends of the body when the cord is reciprocated vertically, said body having an elongated chamber extending longitudinally thereof, and a whistle mounted in a portion of said body and communicating with the intermediate portion of the chamber and with the atmosphere and adapted to be actuated by air passing therethrough, said body being compressed upon deceleration of the translational movement thereof as it approaches the lower extremity of its movement for restricting the chamber and expelling the air therefrom through the whistle and being thereafter returned to a normal expanded position by its resilience for enlarging said chamber to its normal size and whereby the whistle will be actuated by the air passing inwardly therethrough.

5. A toy as in claim 4, the tapered ends of said body being roughened for affording a gripping surface for the cord ends for causing said ends to be wound spirally on the body.

6. A toy as in claim 4, the tapered ends of said body being roughened for affording a gripping surface for the cord ends for causing said ends to be wound spirally on the body, for compressing the body and restricting the chamber as the cord ends are wound onto the intermediate portion of the body.

THOMAS I. NAKANO.
